DESIGN FOR A MILK BOTTLE

William C. Teunisz, Grand Rapids, Mich.

Substitute for abandoned application Serial No. 84,427, April 20, 1939. This application May 9, 1940, Serial No. 92,248. Term of patent 14 years

To all whom it may concern:

Be it known that I, William C. Teunisz, a citizen of the United States, residing at Grand Rapids, in the county of Kent and State of Michigan, have invented a new, original, and ornamental Design for a Milk Bottle, of which the following is a specification, reference being had to the accompanying drawing, forming part thereof.

The single figure of the drawing is a side elevational view of a milk bottle, showing my new design. The bottle is of uniformly circular cross section.

The present case is a substitute for the application filed April 20, 1939, Serial No. D-84,427.

I claim:

The ornamental design for a milk bottle, as shown and described.

WILLIAM C. TEUNISZ.
